UNITED STATES PATENT OFFICE.

LEVI L. ROBERTSON, OF MADISON, MINNESOTA.

ADJUSTABLE SCAFFOLD.

1,115,975.

Specification of Letters Patent.

Patented Nov. 3, 1914.

Application filed June 10, 1914. Serial No. 844,214.

To all whom it may concern:

Be it known that I, LEVI L. ROBERTSON, a citizen of the United States, residing at Madison, in the county of Lac qui Parle and State of Minnesota, have invented certain new and useful Improvements in Adjustable Scaffolds, of which the following is a specification.

My invention relates to improvements in scaffolds wherein an approximately horizontal member is provided, which is longitudinally extensible and vertically adjustable with respect to uprights or supports included therein.

An important object of the invention is to provide apparatus of the above mentioned character, which is simple in construction, inexpensive to manufacture, and convenient in use.

Other objects and advantages of the invention will be apparent during the course of the following description.

In the accompanying drawings forming a part of this specification and in which like numerals are employed to designate like parts throughout the same, Figure 1 is a side elevation of my scaffold showing the horizontal supporting member in the uppermost position, Fig. 2 is a similar view showing the horizontal supporting member in a lower position, Fig. 3 is a horizontal sectional view taken on line 3—3 of Fig. 2, Fig. 4 is a transverse vertical sectional view taken on line 4—4 of Fig. 2, and, Fig. 5 is a transverse section taken on line 5—5 of Fig. 1.

In the drawings, wherein for the purpose of illustration is shown a preferred embodiment of my invention, the numeral 10 designates uprights or upstanding supports, preferably in the form of ladders. These supports or ladders are identical whereby a detailed description of one will suffice for both. Each support or ladder 10 comprises spaced standards 11, which are vertically inclined when the scaffold is in use, as shown. The standards 11 are connected by spaced rungs 12, as is customary. Formed upon the inner sides of the standards 11 adjacent the inner edges thereof are longitudinal recesses 13, within which are adapted to slide links 14. Each link comprises bars or members 14', which are arranged in transversely alined pairs and rigidly connected by suitably spaced rods 15 or the like, forming a surface upon which

the operator may walk. The ends of the adjacent bars 14' have knee joint pivotal connections as shown at 16, which allows the links to be swung upwardly with respect to the supports or ladders 10 but positively preventing them from being swung downwardly beyond a horizontal position.

As above stated, the links 14 are adapted to slide within the longitudinal recess 13, and the same are held therein by means of removable transverse rods 17, detachably connected with the standards 11 and arranged inwardly of the links, as shown. The rods 17 are arranged in spaced superposed relation, whereby each rod in addition to preventing the downward movement of the links, serves as a support for the outermost horizontally arranged link, whereby the horizontally arranged links may be vertically adjusted by removing or replacing the rods 17. The scaffold may be longitudinally expanded or contracted, while the horizontal links remain in the same horizontal plane, by removing or inserting certain of the outer links from or into the recesses 13, as is obvious. The supports or ladders 10 may be folded flat upon each other, the links 14 passing entirely within the recess 13, as is obvious.

The links 14 are provided with transverse openings 18, (see Fig. 5) adapted to receive the hooked ends 18' of diagonal brace rods 19 and 20. The hooked ends 18' are preferably provided with transverse openings, to receive cotter pins 19' or the like, as shown in Fig. 5. The opposite ends of the brace rods 19 and 20 are hooked to engage with eyes 20', secured to the standards, as shown. The brace rods 20 are preferably provided with turn buckles 23, whereby they may be extended or contracted.

The operation of the apparatus is as follows:—When it is desired to elevate the horizontal supporting member formed of the links 14, the upper rods 17 being removed, such supporting member is moved toward the upper ends of the standards 11, the links sliding in the grooves 13, as is obvious. Subsequently to this the upper rods 17 are secured to the standards by being passed through the openings therein, the uppermost rods serving to support the horizontal member. The diagonal braces 19 and 20 are now secured to the standards and horizontal member, for holding these parts in the

proper position. The horizontal member may be lowered to assume the position shown in Fig. 1, as is obvious. It is also obvious that the entire apparatus may be collapsed to lie flat, for the purpose of shipment or storage.

It is to be understood that the form of my invention herewith shown and described is to be taken as a preferred example of the same, and that various changes in the shape, size, and arrangement of parts may be resorted to without departing from the spirit of the invention or the scope of the subjoined claims.

15 Having described my invention, I claim:—

1. In a scaffold, a plurality of spaced upstanding supports, and a member extending between the supports formed of a plurality of pivoted elements with the opposite 20 end elements extending longitudinally of the upstanding supports and adapted to be longitudinally adjusted with relation thereto.
2. In a scaffold, a plurality of spaced upstanding supports, and a flexible member 25 connecting the upstanding supports and formed of a plurality of links having knee joint pivotal connection, certain of the links being arranged within and slidably engaging the upstanding supports to move longitudinally thereof.

3. In a scaffold, a plurality of spaced upstanding supports having longitudinally extending guide means, and a flexible member connecting the upstanding support and formed of a plurality of links adapted for 35 longitudinal movement within the guide means.

4. In a scaffold, a plurality of spaced upstanding supports having longitudinally extending grooves provided with open sides, a 40 flexible member connecting the upstanding supports and formed of a plurality of links having knee joint pivotal connection and adapted for longitudinal movement within the grooves, and removable rods connected 45 with the supports adjacent the longitudinal grooves to retain the links therein.

5. In a scaffold, a plurality of spaced upstanding supports, and an approximately horizontal supporting member extending between the supports and embodying a plurality of relatively movable elements and having the end elements longitudinally adjustably mounted upon the supports.

In testimony whereof I affix my signature 55 in presence of two witnesses.

LEVI L. ROBERTSON.
